UNITED STATES PATENT OFFICE.

FREDERICK CRAIB AND JAMES BARNETT, OF MARTINEZ, CALIFORNIA.

MOP WRINGER.

1,419,543.

Specification of Letters Patent. Patented June 13, 1922.

Application filed October 27, 1920. Serial No. 420,021.

To all whom it may concern:

Be it known that we, FREDERICK CRAIB and JAMES BARNETT, citizens of the United States, residing in the city of Martinez, in the county of Contra Costa and State of California, have invented a new and useful Improvement in a Mop Wringer, of which the following is a specification.

Our invention relates to improvements in mop wringers wherein a slidably and rotatably mounted mophead is operated to twist the strands of a mop to wring fluids therefrom.

The primary object of our invention is to provide an improved mop wringer.

Another object is to provide an improved mop head adapted to facilitate the wringing of fluid from a mop attached thereto.

A further object is to provide a device of simple and durable construction adapted to be operated to twist the strands of a mop attached thereto for wringing fluid from said mop.

We accomplish these and other objects by means of the device disclosed in the drawings forming a part of the present specification wherein like characters of reference are used to designate similar parts throughout said specification and drawings and in which,

Fig. 1. is a broken front elevation of a mop attached to our improved mop-head,

Fig. 2. is a broken side elevation of Fig. 1,

Fig. 3. is a view similar to Fig. 2. with the mophead moved to twist the strands of the mop.

Fig. 4. is an enlarged detail view taken along the line 4—4 of Fig. 2.

Referring to the drawings, the numeral 1 is used to designate in general a mop attached in any suitable manner to a mop-head 2 provided with a shank 3 arranged to be engaged and guided by a bearing 4 pivotally mounted between lugs 6 formed upon the lower part of a sleeve 7 secured to a suitable handle 8. The mop 1 is made preferably from a plurality of twisted strands arranged in loops, but any suitable fibrous material adapted to be attached to the head 2 as a continuous web may be substituted. The webs or twisted strands from which the mop 1 is formed are looped over a stirrup 8 formed integrally with or secured to the sleeve 7, said stirrup 8 extending downwardly therefrom a distance substantially equal to the length of the mop 1.

An operating lever 9 having bifurcations 11 formed at one end thereof is pivotally mounted upon the sleeve 7 by means of a bearing pin 12 rotatably mounted in a lug 14 formed at the upper end of the sleeve 7.

A grip 16 is provided at the outer end of the operating lever 9 to facilitate gripping by the hand of an operator. The bifurcations 11 are arranged to extend at either side of the sleeve 7 to engage the upper end of the shank 3 in a manner hereinafter described.

The shank 3 is made as a screw of relatively steep pitch. In our present practice the shank 3 is formed by twisting a square bar a sufficient number of times to obtain a spiral of the desired pitch. The bearing 4 is apertured to conform to the shape and pitch of the twisted shank 3. The upper end of the shank 3 is provided with a collar 16 rotatably mounted thereon between flanges 17, said collar 16 being provided with bearing pins 18 extending laterally from opposite sides thereof and arranged to be engaged by apertures 19 provided in the outer ends of the bifurcations 11, whereby said bifurcations are rotatably and pivotally secured to the shank 3.

The lower portion of the stirrup 8 is provided with a lateral cross bar 21 upwardly offset at 22 to assist in retaining the mop 1 in operative relation to the end of the stirrup 8.

In operation the mop-head 2 is depressed to the normal position disclosed in Fig. 1 of the drawings, the mop 1 passing through the stirrup 8 and over the offset crossbar 21, and utilized in the usual manner. When it is desired to wring water or other fluid from the mop 1, the operating handle 9, which is arranged to normally lie adjacent the mop handle 8, is moved outwardly and downwardly about the bearing 12, thereby causing a corresponding upward movement of the bifurcated ends 11. As the shank 3 is advanced upwardly through the guide bearing 4, a rotative movement is caused by engagement of the spirally disposed sides of the shank with the correspondingly apertured guide 4. The rotatable collar 16 and the pivotally mounting of the guide 4 upon the lugs 6 permit the simultaneous rotation and longitudinal advancement of the shank 3 and the head 2. As the mop head 2 is advanced the mop 1 is moved upwardly over the stirrup 8, the lower portion of the mop being engaged by the offset crossbar 21 and

causing the mop to be twisted by the rotation of the mop head 2. As the mop head is rotated continuously during the upward movement of the shank 3, the mop becomes 5 twisted to a corresponding degree and the fluid thereby forced out. It is obvious that the greater the number of twists caused in the mop by advancement of the shank 3, the more complete will be the expulsion of 10 fluid therefrom.

A spring 24 may be provided about the shank 3 between the mop head 2 and the bearing 4 to assist in returning the mop to its normal position after having been 15 placed for wringing.

Having thus described our invention what we claim as new and desire to secure by Letters Patent is:

A mop wringer comprising a handle; a 20 sleeve fixedly secured upon one end of the handle; a stirrup formed integrally with said sleeve and extending in longitudinal alignment with the handle to receive one end of a mop; a mop head arranged to engage 25 the other end of said mop; a guide

pivotaly mounted upon the sleeve and having a spiral bore therein; a spiral shank secured upon the mop head and passing upwardly through the spiral bore of the guide, said guide operating to impart a rotative 30 movement to the shank and mop head when said shank is moved longitudinally therethrough; an operating lever pivotaly mounted upon one side of the handle; bifurcations formed upon the lever and extending 35 past the handle upon either side thereof; means for rotatably connecting the shank to said bifurcations whereby rotative movement of the shank and head will operate to move the lower end of the mop into engagement with the stirrup and twist said mop between the head and the stirrup when said operating lever is actuated to move the shank longitudinally through the guide; and means for returning said mop head to a normal position after each operation. 40

In witness whereof we hereunto set our signatures.

FREDERICK CRAIB.
JAMES BARNETT.
